UNITED STATES PATENT OFFICE

CHARLES F. OVERPECK AND FRANCIS MARION ALLEN, OF GREENSBURG, INDIANA

LIQUID-DISPENSING DEVICE

Application filed May 19, 1928. Serial No. 279,069.

This invention relates to coin operated means for dispensing liquids such as gasoline and the like, and is described in one particular form in reference to the accompanying drawings, in which,

Fig. 1, is a front elevation of a dispensing apparatus embodying the invention;

Fig. 2, a side elevation of the apparatus;

Fig. 3, a horizontal transverse section on the line 3—3 in Fig. 1;

Fig. 4, a vertical section through a valve and its stem;

Fig. 5, a detail in side elevation of the bar controlled switch;

Fig. 6, a top plan view of the detail as shown in Fig. 5;

Fig. 7, a horizontal transverse section on the line 7—7 in Fig. 2;

Fig. 8, a vertical section on the line 8—8 in Fig. 7;

Fig. 9, a side elevation of the inner coin pull bar;

Fig. 10, a side elevation of the outer coin pull bar;

Fig. 11, a vertical section on the line 11—11 in Fig. 2;

Fig. 12, a horizontal section on the line 12—12 in Fig. 2; and

Fig. 13, a side elevation of the float actuated switch.

Like characters of reference indicate like parts throughout the several views in the drawings.

In the upper portion of a supporting structure 15, we mount a tank 16 here shown as made of metal though it may be made of any other suitable material such as glass. For the purpose of fully disclosing the invention in one particular form, the commodity to be vended will be hereinafter referred to as gasoline such as is commonly vended for automobile use. The gasoline is drawn from any suitable underground storage tank (not shown) through the pipe 17 by the rotary pump 18 driven by the electric motor 19 and discharged through the pipe 20 into the tank 16, the pipe 20 here shown as passing up through the bottom of the tank 16 (Fig. 1.) and extending upward well toward the top of the tank.

An overflow pipe 21 extends up through the bottom of the tank to terminate at a fixed level so that regardless of the amount of gasoline coming into the tank 16, the level of the gasoline will be the top of 55 the overflow pipe 21, which is preferably returned to the storage tank from which the pipe 17 leads.

A discharge pipe 22 also extends up through the bottom of the tank 16 and has 60 its top end at the same level as that of the overflow pipe 21. The lower end of the discharge pipe 22 is interconnected with a flexible hose 23 which may be used to direct the discharged gasoline to any suitable 65 point, such as an automobile gasoline tank in the usual and well known customary manner.

A guide rod 24 is fixed to the base of the tank 16 and extends vertically up 70 through and beyond the top of the tank 16 to slidably receive thereon the displacement plunger 25, which plunger has an upper tubular extension 26 slidably guided over the rod 24. The plunger 25 is rigidly carried by the horizontal arm 27 which is secured to the extension 26 whereby the plunger 25 may be adjusted vertically in relation thereto. The arm 27 is integrally attached to the upper end of the operating bar 28 which is carried in a vertical position between the outer side of the tank 16 and within the structure 15.

The bar 28 extends downwardly below the tank 16 and has a plurality of teeth 29 cut in one edge to form a rack gear. The bar 28 passes through a bracket 30 which carries a pinion gear 31 in mesh with the rack gear teeth 29. A crank shaft 32 slidably extends through the gear 31 and its short hollow shaft 34 and carries an operating crank 33 on the outer end externally of the structure 15, and has a dog 35 fixed to its inner end normally extended inwardly beyond the end of the shaft 34 by a compression spring 36. A dog 37 is fixed on the end of the shaft 34 whereby, by pulling outwardly on the crank shaft 32 the dog 35 may engage with the dog 37, turning of the crank 33 will then cause the 100

gear 31 to turn and raise or lower the bar 28. Releasing the crank 33 permits the spring 36 to disengage the dogs to permit the bar normally to drop downwardly.

5 A weight 38 is attached to the end of the cable 39 which extends up over around down from the pulleys 40 and 41 and is secured to the arm 27. This weight is sufficiently heavy to bring the bar 28 and the plunger 25 supported therefrom to a normal upper position upon releasing of the crank 33. A cover 42 is fixed over the tank 16, and a conical valve 43 is positioned on the tubular extension 26 by the adjustable collar 44 so that the valve 43 striking against the under side of the cover not only effectually closes any opening around the extension 26 through the cover, but also determines the limit of the upward travel of the plunger 25 caused by the weight 38. This position is such that the under side of the plunger 25 is on a level with the tops of the pipes 21 and 22 so that any downward movement of the plunger will immediately start displacing the gasoline to tend to cause it to over flow into the pipes 21 and 22.

Attached to the under side of the cover 42 is a bracket 45 in which is pivotally carried the lever 46, the lever 46 being mounted off-center to have a longer arm toward the overflow pipe 21 and the shorter arm toward the discharge pipe 22 so that the lever 46 normally tends to have its longer end drop downwardly to raise the shorter end correspondingly. To the outer end of the longer arm of the lever 46 is pivotally secured a hollow valve stem 47, to the lower end of which is affixed a valve head 48 adapted to seat in a conical seat formed in the upper end of the pipe 21. A hole 49 is drilled through the head below its ring of contact in the seat so that there may be a free passage for air in from the top of the stem 47 and out through the hole 49 into the pipe 21 when the valve 48 is seated thereon.

50 A similar valve 50 is carried on a similar stem 51 pivotally suspended from the shorter end of the lever 46, the valve 50 being adapted to be seated in the conical seat in the top end of the discharge pipe 22 (Fig. 1). An adjustable stop screw 52 is carried in the long arm of the lever 46 and is so adjusted as to have its lower end extend through the lever 46 to be contacted on the top side of the plunger 25 to hold the longer arm of the lever 46 upward sufficiently to tightly seat the valve 50 on the pipe 22 and lift the valve 48 from off the pipe 21.

60 Now should the crank 33 be pushed in and turned to pull down the bar 28 so as to force the plunger 25 down into the gasoline, the lever 46 will be permitted to rock back to its normal position with the valve 48 seated on the overflow pipe 21 and the valve 50

lifted from the discharge pipe 22 so that moving the plunger down will displace a definite amount of gasoline which will be raised above the top of the pipe 22 to overflow into it and discharge therethrough.

65 The bar 28 carries a collar 54 secured to it at a position that will just permit the tongue 55 of the slide 56 to enter thereunder when the plunger 25 has been returned to its uppermost position (Figs. 2 and 7). The slide 56 extends normally from the tongue to lie parallel to the front wall 61 of the structure 15, and the tongue 55 is slidably guided through the bracket 62 to permit the slide and the attached tongue to slide toward and away from the wall 61.

70 On the outer side of the collar 54 is fixed an upright arm 63 from which laterally extends a pin 64. A similar pin 65 projects from the side of the tongue 55 parallel to the pin 64. A cross member 66 of the structure 15 carries a bell crank 67 pivotally secured thereto to have one leg hang substantially normal on the side of the pin 66 removed from the bar 28. The horizontally 75 extended arm of the crank 67 is of such length that it is normally below the pin 65 when the bar 28 is up, and when the bar 28 is lowered will be contacted on its top side by the pin 65, be pushed down to rock back 80 and swing over the top side of the pin 65, whereupon upward travel of the bar 28 will cause the pin 65 to contact the arm from below and thereby rock the crank 67 to cause the vertical leg to strike the pin 66 and 85 carry it and the tongue 55 therewith toward the bar 28 so that the end of the tongue 55 will have passed under the collar 54 by the time the crank 67 has been rocked sufficiently to permit the pin 65 to pass around the 90 end of the horizontal arm of the crank and release it.

95 It is now obvious that once the bar 28 has been lowered and raised to its top position, the tongue 55 entered under the collar 100 54 prevents further movement of the bar 28, and means for withdrawing the tongue 55 will now be described.

105 Three bars 68, 69 and 70 are slidably mounted in the bracket 71 to slide perpendicularly from the front wall 61.

110 From the top side of the front end of each bar, a rod extends over the slide 56 and out through the wall 61 to receive the pull knobs 72, 73, 74 respectively thereon. Immediately above the knobs are the slots 175, 176 and 177 of just the right proportions to receive a twenty-five cent piece, a fifty cent piece, and a silver dollar respectively therein, and conductor tubes 76, 77, and 78 115 lead from the slots rearwardly and downwardly to terminate with but slight clearance over the respective bars 68, 69, and 70. Slots 79, 80 and 81 corresponding in size to the respective coins are cut through from 120 125

the top sides of the bars 68, 69 and 70 to curve down and forwardly to open from the front ends of the bars below the forwardly projecting rods.

5 Referring to Figs. 7, 8, 9, and 10, the under sides of the bars 68, 69 and 70 are notched near their forward ends to pass over a stop strip 82 passed normally under all three bars, and the bars are also notched 10 from the under sides near the rear ends to pass over the return lever 83 which is pivoted at one end and has a spring 84 attached by one end to the free end of the lever 83 and by its other end to a post out 15 back of the bars, whereby the lever 83 normally retains the bars 68, 69 and 70 back against the stop strip 82, as in Figs. 7, 8, 9, and 10.

The bar 68 is proportioned so that when 20 it is pulled forwardly by the knob 72 the rear shoulder 85 of the notch over the strip 82 will strike the strip before the front end of the bar strikes the slide 56 when the slide 56 is in its inner position.

25 Releasing the knob 72 will permit the bar lever 83 to automatically return the bar 68 to its normal position which is such that a twenty-five cent piece coming down the conductor tube 76 will drop into the slot 79 and 30 roll against the slide 56 whereupon any pull on the knob 72 will cause the end of the bar 68 to press the twenty-five cent piece against the slide 56, carry along the slide as the bar is moved, and thereby pull the tongue 55 35 out from under the collar 54. Upon releasing the knob 72, the bar 68 returns to its normal rear position and the coin drops by gravity into the money box 86, leaving the slide and tongue in the position indicated.

40 The bar 28 may then be lowered by the crank 33. An adjustable stop 87 is positioned on the bar 28 above the collar 54 to have a down-turned leg that will strike on the tongue 55 when the amount of gasoline 45 to be vended for twenty-five cents has been displaced by the proper travel of the bar 28. The intermediate bar 69 has the notch over the stop strip 82 proportioned so that the forward end of the bar when pulled ahead 50 by the knob 73 may not strike the slide 56 when no coin is therebetween, but is of such length that when the fifty cent piece drops down the slide 56 is moved ahead or forwardly a total distance equal to that moved 55 by the twenty-five cent piece in bar 68 plus the difference in diameters of the twenty-five and fifty cent pieces (Fig. 8), and the coin drops down through the opening 89 upon release of the knob 73.

60 When the bar 69 is actuated as described, the tongue 55 is pulled ahead so that the leg of stop 87 does not strike the tongue 55 but passes on down as the bar 28 is lowered. A second adjustable stop 90 is carried on the 65 bar 28 to have a leg extended forwardly

that will strike the tongue 55 when in the "fifty-cent" position to stop further down travel of the bar 28.

The bar 70 is similarly formed to be operative with a silver dollar pressed 70 against the slide 56 to carry it ahead a distance farther than those reached by the two lesser coins, and a third adjustable stop 91 is carried on the bar 28 to strike the tongue 55 when moved to the "dollar" position. 75 The tongue 55 and slide 56 are, as above indicated, returned after each outward movement to the inner normal position of the tongue 55 being under the collar 54 before again being moved out. 80

When any one of the bars 68, 69, or 70 are pulled ahead, the lever 83 is pulled ahead to come under the collar 54 from the back side so that when the tongue 55 has been withdrawn from under the collar 54 and 85 the particular bar is normally held in the forward position, the bar 28 can not be lowered to permit any person to obtain gasoline thereby over the amount for which he had deposited his coin to originally withdraw the tongue 55. The bar 28 may be held in any position once it is lowered by means of the screw 92 which may be run in against the edge of the bar 28. 90

Unique means are provided to permit re-filling of the tank 16 only when the plunger 25 has been returned to its uppermost position and the bar 28 locked against downward travel. 95

At one side at the lower end of the bar 28 is mounted an electric switch 93 (Figs. 1, 5 and 6) which is normally held closed by the spring 94 which pulls the rod 95 toward the end of the bar 28 to hold the bar 96 in contact across the contacts 97 and 98. 100 The end of the rod 95 is cut to slope downwardly and across under the end of the bar 28 so that downward movement of the bar 28 will cause the bar 28 to press the rod 95 back to overcome the spring 94 and carry 105 the bar 96 away from the contacts 97 and 98. A wire 99 leads from the contact 98 to the motor 19 and a wire 100 leads from the other contact 97 out through the conduit 110 101 to any suitable source of electric current (not shown). 115

A second switch 102 is provided. This switch has the actuating rod 103 carrying the contact bar 104 across one end normally held out of contact with the two contacts 105 and 106 by the compression spring 107. A wire 108 leads from the motor 19 to the contact 105 and a wire 109 leads from the other contact 106 out through the conduit 101 to the source of current to complete the 120 circuit including the switch 93 the motor 19 and the switch 102. 125

A cable 110 is fixed to the outer end of the switch rod 103 and passes up over, around and down from the pulleys 111 and 130

112 in the top of the structure 15 and is attached to the tube 113 extending slidably through the cover 42. The tube 113 is slidably guided in a vertical direction by the rod 114 passing internally therethrough and fixed to the bottom of the tank 16. The tube 113 passes down to within the tank 16 and adjustably carries thereon a float 115.

5 A valve 116 is adjustably fitted on the tube 10 113 under the cover 42 so that when gasoline is at the "full" level in the tank (Fig. 1) the valve 116 effectively closes any slight opening there may be between the tube 113 and cover 42 where the tube passes there- 15 through.

When the plunger 25 is carried down into the gasoline, the level does not drop but raises, and the float 115 does not drop then, but when the plunger 25 is returned to its 20 top position the level of the gasoline drops and the float 115 drops accordingly to pull on the cable 110 and thereby close the switch 102, the switch 102 being usually closed thereby before the bar 28 has reached 25 its upper limit of travel. As soon as the bar 28 comes up the switch 93 then closes, and as both switches 93 and 102 are closed the motor 19 may then function to operate the gasoline pump. As soon as the gasoline 30 comes up to the predetermined level, the float 115 is raised sufficiently to release the pull on the rod 103 of the switch 102 which it has held closed, so that the motor 19 is then stopped. It is obvious that even 35 though the switch 102 may close before the plunger 25 reaches its uppermost position, no gasoline will be pumped until the plunger 25 does reach that position to permit closure of the switch 93.

40 A further means to prevent unwarranted dispensing of gasoline is provided. A door 126 is provided to permit access to the pump and motor. When this door is opened, a pawl 117 is carried under the end of the 45 bar 28 by the link 118 pivotally interconnecting the door and the pawl. The door 126 can not be opened unless the bar 28 is at the top position since the pawl will strike the edge of the bar 28 in any other position.

50 Having described our invention in the one form now best known to us, it is obvious that many structural variations may be made without departing from the spirit of the invention, and we, therefore, do not desire to be limited to the precise form as shown and described nor any more than may be required by the following claims.

We claim:

1. In a liquid dispensing device, a supporting structure, a tank having a discharge opening therefrom adapted to hold a liquid to the level of the opening, a plunger, and means for carrying the plunger into the liquid to raise its level above said opening, 60 and means for automatically returning the

70 plunger to its initial position following a selective predetermined travel of the plunger, means for filling said tank, and means operated by change in level of the liquid normally setting said filling means in action.

2. In a liquid dispensing device, a supporting structure, a tank having a discharge opening therefrom adapted to hold a liquid to the level of the opening, a plunger, and means for carrying the plunger into the 75 liquid to raise its level above said openings, said tank having an overflow opening therefrom normally open, and means for closing said overflow opening upon downward travel of the plunger, and means for automatically 80 returning the plunger to its initial upper position following a selective predetermined travel of the plunger and uncovering said overflow opening float means in the tank, and means for filling said tank operative 85 in association with the combined travel of the plunger and the float means.

3. In a liquid dispensing device, a supporting structure, a tank having an overflow opening normally open, and a discharge 90 opening, a plunger normally suspended to have its underside substantially at the level of the overflow opening, a bar fixed to said plunger, means for moving said bar downwardly, means returning said bar and 95 plunger to their normal positions upon release of said moving means, and valve means closing said overflow opening upon down movement of the plunger, filling means for placing liquid in the tank, and control means 100 holding inoperative said filling means when said plunger is removed from its normal position, and a second control means in series relation with said first control means holding said filling means inoperative when 105 the level of the liquid in the tank is at or above the overflow opening.

4. In a liquid dispensing device, a supporting structure, a tank having an overflow opening normally open, and a discharge 110 opening, a plunger normally suspended to have its under side substantially at the level of the overflow opening, a bar fixed to said plunger, means for moving said bar downwardly, means returning said bar and plunger to their normal positions upon release of said moving means, and valve means closing said overflow opening upon down movement of the plunger, a slide normally engaging said bar when in its normal upper 115 position and holding it against downward movement, a coin actuated mechanism for moving said slide out of engagement with the bar to predetermined distances therefrom, and stops spaced apart on the bar and projecting varying distances therefrom in accordance with said distances of the slide thereby determining selective definite levels to which the said bar may be lowered.

5. In a liquid dispensing device, a sup-

- porting structure, a tank having an over-flow normally open, and a discharge opening, a plunger normally suspended to have its under side substantially at the level of the overflow opening, a bar fixed to said plunger, means for moving said bar downwardly, means returning said bar and plunger to their normal positions upon release of said moving means, and valve means closing said overflow opening upon down movement of the plunger, a slide normally engaging said bar when in its normal upper position and holding it against downward movement, a coin actuated mechanism for moving said slide out of engagement with the bar to predetermined distances therefrom, and stops spaced apart on the bar and projecting varying distances therefrom in accordance with said distances of the slide thereby determining selective definite levels to which the said bar may be lowered, and interlocking means engaging said bar during the operation of said coin actuated mechanism.
6. In a liquid dispensing device, a supporting structure, a tank having an over-flow opening normally open, and a discharge opening, a plunger normally suspended to have its under side substantially at the level of the overflow opening, a bar fixed to said plunger, means for moving said bar downwardly, means returning said bar and plunger to their normal positions upon release of said moving means, and valve means closing said overflow opening upon down movement of the plunger, a slide normally engaging said bar when in its normal upper position and holding it against downward movement, a coin actuated mechanism for moving said slide out of engagement with the bar to predetermined distances therefrom, and stops spaced apart on the bar and projecting varying distances therefrom in accordance with said distances of the slide thereby determining selective definite levels to which the said bar may be lowered, and filling means for causing liquid to flow into the tank, a filling means control associated with said bar whereby the control is operative only when the bar is in the normal upper position, and a second control actuated by float means in the tank, said second control interacting with said first control and operative only when the level of liquid falls below said overflow opening.
7. In a liquid dispensing device, a tank having an overflow opening and a discharge opening, a plunger substantially smaller in diameter than that of the tank, a bar secured to said plunger, an overflow opening valve held away from said opening by the plunger when in its normal position said valve closing the opening upon downward travel of the plunger, means for pulling the bar upwardly, a stop associated with and determining the upper limit of travel of the plunger so as to have its under face substantially at the level of said overflow opening, crank means for overcoming said upward pulling means for carrying the bar downward, a plurality of stops on the bar, and a member adapted to be selectively moved toward and away from the bar to intercept said stops as desired, said member engaging said bar to prevent downward movement, a discharge opening valve normally closing said discharge opening and means operative by travel of the plunger for opening said valve upon downward travel of the plunger.
8. In a liquid dispensing device, a tank having an overflow opening and a discharge opening, a plunger substantially smaller in diameter than that of the tank, a bar secured to said plunger, an overflow opening valve held away from said opening by the plunger when in its normal position, said valve closing the opening upon downward travel of the plunger, means for pulling the bar upwardly, a stop associated with and determining the upper limit of travel of the plunger so as to have its under face substantially at the level of said overflow opening, crank means for overcoming said upward pulling means for carrying the bar downward, a plurality of stops on the bar, and a member adapted to be selectively moved toward and away from the bar to intercept said stops as desired, said member engaging said bar to prevent downward movement, and coin actuated means determining the movement of said member.
9. In a liquid dispensing device, a supporting structure, a tank having an over-flow opening normally open, and a discharge opening, a plunger normally suspended to have its under side substantially at the level of the overflow opening, a bar fixed to said plunger, means for moving said bar downwardly, means returning said bar and plunger to their normal positions, upon release of said moving means, and valve means closing said overflow opening upon down movement of the plunger, a slide normally engaging said bar when in its normal upper position and holding it against downward movement, a coin actuated mechanism for moving said slide out of engagement with the bar to predetermined distances therefrom, and stops spaced apart on the bar and projecting varying distances therefrom in accordance with said distances of the slide thereby determining selective definite levels to which the said bar may be lowered, and means for returning said slide to its normal position engaging said bar.
10. In a liquid dispensing device, a tank having an overflow opening and a discharge opening, a plunger substantially smaller in diameter than that of the tank, a bar se-

- cured to said plunger, an overflow opening valve held away from said opening by the plunger when in its normal position said valve closing the opening upon downward travel of the plunger, means for pulling the bar upwardly, a stop associated with and determining the upper limit of travel of the plunger so as to have its under face substantially at the level of said overflow opening, crank means for overcoming said upward pulling means for carrying the bar downward, a plurality of stops on the bar, and a member adapted to be selectively moved toward and away from the bar to intercept said stops as desired, said member engaging said bar to prevent downward movement, and means for automatically returning said member to its normal position actuated by upward movement of said bar following said selective movement.
11. In a liquid dispensing device, a liquid holding tank, a discharge standpipe within the tank, an overflow standpipe within the tank, the tops of said standpipes being substantially at the same level and considerably below the top of the tank, a cover on said tank, a lever pivotally hinged over the tank, a valve pivotally suspended by a stem from each end of the lever, said lever being so hinged as to have the combined center of gravity of the lever and valves removed from the hinge point toward the overflow pipe, and to have one of said valves normally tending to seat in the end of the overflow pipe and the other valve adapted to seat in the end of the discharge pipe upon rocking of the lever, a plunger adapted to travel downwardly in said tank, a bar supporting said plunger, yielding means normally holding said plunger in an upper position, in which position said plunger causes said overflow pipe valve to be lifted and the discharge pipe valve to be closed, a plurality of stops on said bar, a slide, means for moving said slide to be in the path of any of said stops as desired, means for pulling down said bar, means for filling said tank, and control means associated with said bar preventing the operation of said filling means until said bar returns to its normal position.
12. In a liquid dispensing device, a tank having a discharge opening therefrom spaced above the bottom of the tank, a valve normally closing said discharge opening, a coin operated mechanism, and means operatively associated with said valve and said mechanism for permitting said valve to be opened and making available a predetermined quantity of liquid for discharge through said opening upon operation of said mechanism.
13. In a liquid dispensing device, a tank having a discharge opening therefrom spaced above the bottom of the tank, a valve

normally closing said discharge opening, a coin operated mechanism, and means operatively associated with said valve and said mechanism for permitting said valve to be opened and making available a predetermined quantity of liquid for discharge through said opening upon operation of said mechanism, and tank refilling means automatically functioning following the completion of said discharge.

14. In a liquid dispensing device, a tank having a discharge opening therefrom spaced above the bottom of the tank, a valve normally closing said discharge opening, a coin operated mechanism, and means operatively associated with said valve and said mechanism for permitting said valve to be opened and making available a predetermined quantity of liquid for discharge through said opening upon operation of said mechanism, said operatively associated means comprising a bar interconnecting with said coin mechanism and releasing said valve upon release by said coin mechanism.

15. In a liquid dispensing device, a tank having a discharge opening therefrom spaced above the bottom of the tank, a valve normally closing said discharge opening, a coin operated mechanism, and means operatively associated with said valve and said mechanism for permitting said valve to be opened and making available a predetermined quantity of liquid for discharge through said opening upon operation of said mechanism, said operatively associated means comprising a bar interconnecting with said coin mechanism and releasing said valve upon release by said coin mechanism, and a plunger carried by the bar for varying said quantity of liquid.

16. In a liquid dispensing device, a tank having a discharge opening therefrom spaced above the bottom of the tank, a valve normally closing said discharge opening, means operatively associated with said valve for causing the valve to be opened and raising a predetermined quantity of liquid within the tank above said opening for discharge therethrough upon operation of said means, and tank refilling means automatically functioning following the completion of said discharge, the discharge from said refilling means being removed from said tank discharge opening valve.

In testimony whereof we affix our signatures.

CHARLES F. OVERPECK.
F. MARION ALLEN.
